UNITED STATES PATENT OFFICE.

JOHN R. SINCLAIR, OF HOLYOKE, MASSACHUSETTS.

DANDY-ROLL.

1,140,856.

Specification of Letters Patent. Patented May 25, 1915.

Application filed October 22, 1914. Serial No. 863,000.

To all whom it may concern:

Be it known that I, JOHN R. SINCLAIR, a citizen of the United States of America, and resident of Holyoke, in the county of Hampden and State of Massachusetts, have invented certain new and useful Improvements in Dandy-Rolls, of which the following is a full, clear, and exact description.

This invention relates to improvements in 10 dandy rolls to be employed in Fourdrinier paper machines, the features of invention being also as well applicable in the cylinders of cylinder paper machines.

The object of the invention is to render 15 the outer gauze covering of the roll by which the letters or configuration for imparting the water mark are carried, removable from the openwork or skeletonized cylindrical supporting structure or body so 20 that different outer gauze coverings may be interchangeably used on one body, with the result of material saving in a paper mill, especially where comparatively small quantities of paper with a given water mark are 25 to be produced.

The invention is described in conjunction with the accompanying drawings, and set forth in the claims.

In the drawings:—Figure 1 is a plan view 30 of a portion of the length of a dandy roll, in which my improvements are embodied. Fig. 2 is a cross sectional view on line 2—2, Fig. 1. Fig. 3 is a partial longitudinal section, on an enlarged scale, on line 3—3, Fig. 35 1. Fig. 4 is an enlarged cross section for more clearly showing certain features of construction, than is done in Fig. 2.

The dandy roll body or open work cylindrical structure which supports the outer 40 gauze covering A may be of any of the several and well known and approved constructions, the same comprising end heads a with journals b, ring-like or annular supports d, parallel longitudinal wires e running from 45 end to end of the roll and connected with the annular supports and the winding wires f, the spacing between the convolutions of which are uniform.

In this new dandy roll or paper machine 50 cylinder, a foraminous covering B is supported directly by and secured on the winding wires, the same nearly, but not quite circumferentially encircling the body; but

leaving a longitudinal space g between its approached parallel edges. 55

D D represent a pair of strips of flat rigid metal adapted to be disposed, side by side, in edgewise contact in the aforementioned longitudinal space g. These strips have inwardly extended regularly spaced tubular 60 studs h made with recesses i i in their opposite sides and having convergently formed ends k whereby they are adapted for entrance between and engagement with the winding wires, serving as retainers for the 65 said strips in their places in the space or channel g, bottoming on the outer surface of the winding wires and having their outer faces flush or in continuity with the contour of the surface of the aforementioned 70 layer B of foraminous material.

The outer gauze roll covering A (which carries the watermarking appliances as usual) has the edge portions thereof overlapped across the outer sides of, and secured to, said flat rigid strips d d, such security being by stitching through small perforations therefor in the plates or by soldering. When this outer covering is to be applied and retained on the roll it is 80 brought to encircling engagement about the body, its edgewise provided strips being disposed in the longitudinal space or channel g, the studs h h, of which a sufficient number are provided, being forced or snapped 85 to their engagements between the winding wires. The edges of the gauze covering A are so extended clear to the meeting edges of the strips D D that when such strips are matched together and detachably confined 90 in their places the said covering A is to all intents and purposes circumferentially continuous and with no tendency to leave a seam mark perceptible in the finished paper. When desired to substitute one gauze outer 95 cover A for one which had been heretofore used on the roll, it is only necessary to pry the strips D D in the proper direction whereby the studs thereof become disengaged from the winding wires, leaving the 100 covering free to be unwrapped from the roll body which is then in readiness for the reception of another covering of like structural character. The studs are preferably tubular and the metallic strips or long narrow plates D D are drilled with a greater or

less number of perforations m , rendering same foraminous in degree substantially corresponding to the character of the portion of the body which includes the layer B of 5 coarse gauze or equivalent material.

I claim:—

1. In a dandy roll, the combination with the cylindrical openwork supporting structure including the usual regularly spaced 10 winding wires, and a foraminous covering supported by the winding wires, nearly but not quite circumferentially encircling same, and leaving a longitudinal space between its approached parallel edges, of a pair of 15 strips of flat rigid material adapted to be disposed side by side in said longitudinal space, and having inwardly extended regularly spaced members adapted for entrance between, and for engagement with, the winding wires, and the outer gauze roll covering having the edge portions thereof overlapped across the outer sides of, and secured to said flat rigid strips.
2. In a dandy roll, the combination with 25 the cylindrical openwork supporting structure including the usual regularly spaced winding wires, and a foraminous covering supported by the winding wires, nearly but not quite circumferentially encircling same, 30 and leaving a longitudinal space between its approached parallel edges, of a pair of strips of flat rigid material adapted to be disposed side by side in said longitudinal space, and having inwardly extended regularly spaced studs made with opposite recessed sides and convergently formed ends 35 adapted for entrance between, and for engagement with, the winding wires, and the outer gauze roll covering having the edge portions thereof overlapped across the outer sides of, and secured to, said flat rigid strips.
- 40 3. In a dandy roll, the combination with portions thereof overlapped across the outer sides of, and secured to, said flat rigid strips.

the cylindrical openwork supporting structure including the usual regularly spaced winding wires, and a foraminous covering 45 supported by the winding wires, nearly but not quite circumferentially encircling same, and leaving a longitudinal space between its approached parallel edges, of a pair of strips of flat rigid material adapted to be 50 disposed side by side in said longitudinal space, and having inwardly extended regularly spaced tubular studs made with opposite recessed sides and convergently formed ends adapted for entrance between, and for engagement with, the winding wires, and the outer gauze roll covering having the edge portions thereof overlapped across the outer sides of, and secured to, said flat rigid strips.

4. In a dandy roll, the combination with the cylindrical openwork supporting structure including the usual regularly spaced winding wires, and a foraminous covering supported by the winding wires, nearly but not quite circumferentially encircling same, 60 and leaving a longitudinal space between its approached parallel edges, of a pair of strips of flat rigid material made with perforations therethrough adapted to be disposed side by side in said longitudinal space, and having inwardly extended regularly spaced tubular studs made with opposite recessed sides and convergently formed ends adapted for entrance between, and for engagement 65 with, the winding wires, and the outer gauze roll covering having the edge portions thereof overlapped across the outer sides of, and secured to, said flat rigid strips.

Signed by me at Springfield, Mass., in presence of two subscribing witnesses.

JOHN R. SINCLAIR.
